James Wager, Volney Richmond, & Harvey Smith of Troy, N. Y.
Letters Patent No. 515 Dated Oct. 26th 1852.

The schedule referred to in these Letters Patent and making part of the same.

To all whom it may concern:

Be it known that we, James Wager, Volney Richmond and Harvey Smith, of the City of Troy, in the County of Rensselaer, and State of New York, have invented or produced a new design and configuration to be cast upon the plates of a cooking stove, and we do hereby declare that the following is a full clear and exact description of the character which distinguishes it from all other things before known reference being had to the accompanying drawings, making part of these specifications.

Fig 1 is a perspective view of the stove showing our design to consist of certain ornamental plates of peculiar configuration to suit the purposes of the stove to which it is adapted and representing the several plates in their proper places

Fig 2. represents the ornaments of full size upon the oven or side doors and are composed of triangular fillets arranged in hexangular compartments.

Fig 3. shows in full size ornaments upon the panels of the back plate (Fig 4) being triangular fillets running diagonally across the panel and abutting at their intersections against small hemispheres.

Fig 4. is a geometrical elevation of the back plate showing the manner in which the central projection (forming the up pipe) is finished on the angles viz having quarter circles sunk from the faces adjoining similar to the central part of Fig 9. and terminated at the top and bottom with cimicistas also showing the corbel A. forming the projection under the pipe collar also forming the panel on each side of the central projection these panels have the margins beveled and trefoil heads and are overlaid by the triangular fillets described in Fig 3.

Fig 5, is a vertical section through the front part of the bottom plate and the elevated hearth as shown in Fig 1. The moulding upon the edge of the bottom plate is a cove and bead and is fluted in such a manner as to present a surface alternately concave and convex - the upper edge of this cove is fluted in a similar manner having the concave part opposite the convex part of the face. The moulding on the lower part of the elevated hearth is an O. C. as seen at B. Fig 5 & C. Fig 1 - above this moulding is a broad belt enriched with flutes and fillets - above this belt is an O. C. moulding forming the border of the hearth - D in Fig 1. is a loose or detached plate or ash pit cover - E, in Fig 1. is a draft slide with a cove moulding F, slanting under the front doors of the stove and attached by a sliding hub (G) to the plate D. Fig 6 is a horizontal section through the side door N, in Fig 1. This door has a cove and bead moulding (J) in Fig 7, and is ornamented with three dwarf minarets (O P Q) shown in the elevation on the door in Fig 1. - Fig 8 is a horizontal section through a part of one of the front doors including the central ornament - The edges of these doors are finished with cove and bead moulding (J) the panels have an O.C. and bead (K) this moulding at the head of the panels is formed into triple arches, supported by cusps of an octangular plan. In the upper corner of these doors (L) is placed small quatrefoil panels as shown in Fig 11. - Fig 8 is a section through the edge of the oven doors these doors are ornamented with triangular fillets arranged in hexangular compartments, as shown in full size in Fig 2. - Fig 9. is a horizontal section through either of the corners of the stove - Fig 10. is a vertical section through the edge of the top plate of the stove - Fig 11. is a small quatrefoil panel in the upper corners of the front doors.

Having thus fully described our improvement what we claim therein as new and for which we desire to secure Letters Patent is the above described ornamental design and configuration of the plates as represented.
